F. H. BURKHART.

LIGHTNING ARRESTER.

APPLICATION FILED MAR. 6, 1917.

1,246,712.

Patented Nov. 13, 1917.

UNITED STATES PATENT OFFICE.

FREDERICK H. BURKHART, OF TRENTON, NEW JERSEY.

LIGHTNING-ARRESTER.

1,246,712.

Specification of Letters Patent. Patented Nov. 13, 1917.

Application filed March 6, 1917. Serial No. 152,630.

To all whom it may concern:

Be it known that I, FREDERICK H. BURKHART, a citizen of United States, residing at 435 Princeton avenue, Trenton, in the county 5 of Mercer and State of New Jersey, have invented new and useful Improvements in Lightning-Arresters, of which the following in a specification.

This invention relates to lightning arresters, and has for an object to provide an 10 efficient and practical device adapted for service in protecting electrical circuits, and more particularly the instruments carried thereby, from the damaging effects of lightning, and other high potential currents.

Another object of the invention resides in 15 a device of the above character, wherein is embodied a conductor strap having opposed terminals thereof connected with the wires 20 of an electrical circuit, portions of the strap being substantially arched, and are slightly spaced from a grounding core, whereby the strap will be enabled to carry a normal current without transmitting the latter to the 25 grounding core, but when a high potential for excessive current is imparted to the strap, said current, by reason of its potential, will leap the gap existing between the strap and the grounding core, so as to be 30 conveyed by the latter to a point of safe discharge, thus enabling the instruments forming a part of said circuit, to be protected from injury.

A further object rests in a lightning arrester having the various elements comprising the same so inter-related, that in the event of one or more of the elements becoming broken or damaged, the offending parts 35 may be readily removed, and new parts substituted in place thereof, without in any way affecting the other elements of the arrester.

Other objects reside in an arrester of the 40 above character, which will be reliable and efficient in operation, economically manufactured, capable of being readily and quickly assembled and of durable and substantial construction.

The preferred embodiment of the invention 45 is represented in the accompanying drawing, forming a part of this specification, in which similar characters of reference indicate like parts throughout the several views thereof.

Figure 1 is a front elevation of a pair of 50 coöperating lightning arresters, constructed

in accordance to the principles of the present invention.

Fig. 2 is a side elevation thereof.

Fig. 3 is a vertical longitudinal sectional view taken along the line 3-3 of Fig. 1. 60

Fig. 4 is a horizontal sectional view taken along the line 4-4 of Fig. 1.

Fig. 5 is a detail perspective view of the conductor strap.

Fig. 6 is a similar view of the grounding 65 core.

Fig. 7 is a perspective view of one of the removable core elements.

Fig. 8 is a diagrammatic view disclosing the arresters as applied to an electrical circuit. 70

Referring more particularly to the drawing, in the preferred embodiment of my invention I employ a plurality of lightning arresters 1, each of which consists of an insulated base 2, upon which the elements of the arrester are mounted, and to provide means for facilitating the securing of the arresters to a wall or panel 3. To effect the securing of the arrester to the wall, the base 75 2 is provided with a plurality of vertically aligned, spaced, countersunk openings 4, which are primarily adapted to receive securing elements 5, the latter being screwed into the wall 3, whereby the arrester will be 80 rigidly secured in a working position.

Binding or terminal posts 6 and 7 are carried by each base 2, and are located in spaced relation, said posts being threaded to receive binding nuts 8, through the use of which 90 the arresters may be wired to an electrical circuit. Each arrester is provided with a conductor 9, which is employed to bridge the gap existing between the posts 6 and 7. In this instance, the conductor is formed from a relatively flat strip of metal, having the medial portions thereof substantially arched, as at 10, and having the extremities thereof provided with openings, which openings are employed to receive the posts 6 and 7, whereby the terminals of the arrester will be 95 connected for electrical communication. The conductors 9 are usually secured in position through the agency of the binding nuts 8.

Positioned within the arched portions 10 105 of the conductors 9 are grounding cores 11, preferably formed from high-grade steel. Each core is provided with an inwardly extending stud 12, which is positioned within an opening 13 provided in the central por- 110

tion of the base 2. The cores 11 are formed to provide annular grooves 14 for the reception of removable semi-circular plates 15, which normally lie wholly within said 5 grooves, the inner plates being provided with openings 16 for the reception of the inwardly extending studs 12.

Interposed between the inner plates 15 and the bases 2 are plates 17, the latter being 10 formed with openings 18 for the reception of the studs 12, and are further provided with inwardly extending lugs 19, operable to engage with the members 2, so as to retain the plates 17 in fixed positions. It will 15 be noted upon referring to Figs. 2 and 3 of the drawing that the margins of the plates 17 are slightly spaced from the conductors 9 so as to define "sparking gaps" 20 therebetween. The grounding cores are 20 further insulated from the conductors 9, through the provision of insulation strips 21, the latter surround the plates 15 and prevent the latter from engaging with the substantially arched portions 10 of the conductors 9. The cores 11 are further provided with central threaded openings 22 which terminate at one end in enlarged bores 23, the latter being employed to receive the extended bosses integrally formed 25 upon one side of said cores. This construction enables the cores 11 to be electrically connected. A common grounding wire may 30 be readily connected with one extremity of the cores through the agency of a binding 35 screw 25, the latter being adapted to be threaded into one of the openings 22, so as to frictionally bind said grounding wire to the cores.

In operation, the arresters 1 are set up in 40 the multiple formation disclosed in Fig. 1, and are preferably positioned within a housing or station 26, and lead wires 27 and 28, leading from any suitable source of extraneous power, are extended to the arresters and are connected with the terminal 45 posts 6 thereof. Other wires 29 and 30 are similarly connected with the lower binding posts 7, and extend to a motor, or any other electrical instrument or device, mounted 50 within the station 26. Thus the motor circuit can be traced by way of the wire 27 to the binding post 6, thence by one of the conductors 9 to the wire 29. Then through 55 the motor 31 to the wire 30, and from the wire 30, by virtue of one of the conductors 9, to the wire 28, thence to the negative side 60 of a source of energy. Thus it will be evident that under normal conditions the arresters 1 will not interfere with the progress 65 of current through the motor circuit above described, and that the space existing between the plates 17 and the conductors 9 and the insulating strips 21, will prevent said circuit from being short-circuited by 65 the grounding core mechanism.

In the event of lightning engaging with the wires 27 and 28 so as to be conducted by the latter, the effects of this high-potential current will be prevented from engaging with the motor 31 through the provision 70 of the arresters 1. This is due to the fact that when an excessive current is being conveyed by the conductors 9, the same will jump the sparking gaps 20, so as to be conducted by the plates 17 and 15 to the grounding cores 11, from which this excessive current is conveyed by means of a wire 32 to a suitable ground 33. This feature, that is the jumping of an excess current from the conductors 9 to the cores 11, is further insured by providing the marginal edges of the conductors 9 at points along the substantially arched portions 10 thereof, with a plurality of spaced notches 23', which leave fingers 35 projecting from the conductors. 80 Said fingers extend beyond the edges of the strips 21, and overlie the removable plates 15. Thus if all of the excessive current carried by the conductors 9 should fail, for any reason, to be conveyed to the cores 90 11 by way of the plates 17, the same will leave the conductor along any of the positions defined by the fingers 35, as will be clearly understood, said fingers being also employed to prevent current discharged 95 from the conductors 9 to the cores 11, from jutting forth in sheet formation, but on the other hand insures a clean sharp spark between the said members.

From the foregoing it will be seen that 100 there is provided a device in which the objects of the present invention have been achieved, and that all of the advantageous features above mentioned are, among others, present. The device is reliable in every respect, capable of being economically manufactured, and in the event of any of the parts becoming broken or out of order, the same may be readily removed and new parts substituted in place thereof, without in any 105 way affecting the remaining elements of the arrester. This is particularly true with reference to the copper plates 15, which receive the brunt of the effects of lightning when transmitted to the arrester, as when 110 said plates are damaged they may be removed from the core without necessitating the discarding of the latter. By forming the cores 11 from steel, the efficiency of the arrester is greatly enhanced, as lightning 115 will endeavor to reach the cores by reason of the inherent lightning attractive properties of the steel cores.

As many changes could be made in the 120 above construction, and many apparently 125 widely different embodiments of this invention could be made without departing from the scope thereof, it is intended that all matter contained in the above description, or shown in the accompanying draw- 130

ings, shall be interpreted as illustrative, and not in a limiting sense.

Having described the invention what is claimed as new and patentable is:

- 5 1. A lightning arrester, comprising an insulated base, wiring terminals carried by said base, a strap of conducting material operable to bridge said terminals, and having a substantially arch-shaped portion 45
40 formed therein, and a grooved grounding core mounted upon said base and disposed within the arched portion of the strap, and a spacing member mounted in the groove of the core. 50
- 15 2. A lightning arrester, comprising an insulated base, circuit terminals carried by said base, a conductor operable to be associated with said terminals, said conductor having the medial portion thereof substantially arched, and a grooved grounding core 55 shaped to conform to the arched portion of said conductor, and means arranged in the groove of the core for spacing the core from said conductor. 60
- 25 3. A lightning arrester, comprising a plurality of spaced wiring terminals having an insulated mounting, a conductor of relatively flat strap-like formation operable to be connected with said terminals, a grounding element located contiguous to said conductor, but slightly spaced therefrom in order to define a sparking gap, and a removable plate section carried by said grounding element, and utilized to protect the latter 65 from the effects of excessive currents. 70
- 30 4. A lightning arrester, comprising a plurality of spaced wiring terminals having insulated mountings, a conductor of flat strap-like formation operable to connect said terminals, the medial portion of said conductor being substantially arched and provided 75
35 with a series of fingers on the edges thereof, a grounding core of substantially circular construction, adapted to be positioned adjacent to the arched portion of said conductor, and located in spaced relation with the latter, whereby an abnormal current passing through said conductor, will be transmitted to said grounding core, substantially as described. 80
- 40 5. A lightning arrester, comprising an insulated base, wiring terminals secured to said base, a strap of conducting material adapted to be connected with said terminals, the medial portion of said strap being substantially arched, and provided with serrated edges, a grounding core associated with said base, and disposed within arched portion of said strap, removable plates operable to fit within an annular groove formed 85 in said core, and a plate interposed between said core and said base, and adapted to conduct excessive currents carried by said strap to said plates and their coöperating core. 90
- 45 6. A lightning arrester, comprising an insulated base, wiring terminals secured to said base, a strap of conducting material adapted to be connected with said terminals, the medial portion of said strap being substantially arched, and provided with serrated edges, a grounding core associated with said base, and disposed within arched portion of said strap, removable plates operable to fit within an annular groove formed 95 in said core, and a plate interposed between said core and said base, and adapted to conduct excessive currents carried by said strap to said plates and their coöperating core, and binding means carried by said core, and operable to secure a grounding wire thereto. 85

In testimony whereof I affix my signature.
FREDERICK H. BURKHART.
